UNITED STATES PATENT OFFICE.

WILLIAM R. BURRAGE, OF TORONTO, ONTARIO, CANADA.

BAG-HOLDER.

SPECIFICATION forming part of Letters Patent No. 398,817, dated March 5, 1889.

Application filed August 6, 1888. Serial No. 282,046. (No model.)

To all whom it may concern:

Be it known that I, WILLIAM RABY BURRAGE, of the city of Toronto, in the county of York, in the Province of Ontario, Canada, have invented a certain new and Improved Bag-Holder, of which the following is a specification.

The object of the invention is to design a simple device by which a bag may be supported and its mouth held open any desired width within the scope of the diameter of the bag; and it consists in the peculiar construction and combination of parts, all as more fully hereinafter described and claimed.

Figure 1 is a perspective view of my improved bag-holder in operation, one side of the mouth of the bag being held more open than the other side. Fig. 2 is a perspective view of the bag-holder without the bag.

In the drawings, A represents the frame, which is bent substantially as shown, one side, a, being bent upwardly, and the side opposite to the bent side being preferably left open, as indicated.

B are jaws formed upon or attached to the frame A. These jaws are shaped to fit over the support by which the bag is to be carried.

C are upwardly-projecting studs or fingers adjustably fitted onto the frame A. These

parts constitute my simple bag-holder, to use which it is merely necessary to fold outwardly the edge of the bag D and slip the fold over the bent side a of the frame A. Then insert the studs or fingers C into the fold and move the said studs or fingers C away from the side a until the mouth of the bag has been distended sufficiently to permit of it being filled. As the studs or fingers C are independently adjustable, and will be held by the tension of the bag at any desired point at which they may be set, the party using my bag-holder is enabled to instantly and easily extend the mouth of the bag to any desired size or angle.

What I claim as my invention is—

A bag-holder consisting of a frame, A, having downwardly-projecting jaws B, and an upwardly-bent side, a, extended above the top of said jaws, in combination with the studs or fingers C, adjustably fitted onto the frame A, and arranged in conjunction with the bent side a, to hold open the mouth of the bag D they are supporting, substantially as and for the purpose specified.

Toronto, July 23, 1888.

WILLIAM R. BURRAGE.

In presence of—

CHARLES C. BALDWIN,
J. M. JACKSON.
